Primary Examiner — Richard E Chilcot(74) **Attorney, Agent, or Firm** — Sterne, Kessler, Goldstein & Fox PLLC**(57) CLAIM**

The ornamental design for a display screen or portion thereof with graphical user interface, as shown and described.

DESCRIPTION

The FIGURE is a front view of a display screen or portion thereof with graphical user interface showing my new design. The broken line showing a display screen or portion thereof forms no part of the claimed design.
